UNITED STATES PATENT OFFICE.

ANDREW KALLIO, OF SOUTH RANGE, MICHIGAN.

FOLDING BED.

1,097,100.

Specification of Letters Patent. Patented May 19, 1914.

Application filed November 18, 1913. Serial No. 801,634.

To all whom it may concern:

Be it known that I, ANDREW KALLIO, a citizen of the United States, residing at South Range, in the county of Houghton 5 and State of Michigan, have invented certain new and useful Improvements in Folding Beds; and I do declare the following to be a full, clear, and exact description of the invention, such as will enable others skilled in the art to which it appertains to 10 make and use the same.

This invention relates to improvements in folding beds and more particularly to those employing lazy-tong side members.

15 The primary object of the invention is to provide a bed of this character which, when not in use, may be folded in a very small space and used as a table or stand.

A secondary object is to provide a simple 20 and efficient means for pivotally connecting the ends of the lazy-tong links and for supporting the same.

With these objects in view, the invention resides in certain novel features of construction and combination herein described 25 and claimed and shown on the drawings wherein:—

Figure 1 is a perspective view of my improved bed in open position. Fig. 2 is a 30 similar view showing the same folded and in the form of a table. Fig. 3 is an end view in folded position, and Figs. 4 and 5 are detail vertical sections through the upper and lower connecting brackets of the 35 lazy-tong structure.

In the drawings, I have shown my improved bed as comprising in general, lazy-tong side members 1 and a spring 2 supported thereon.

40 Coming now more particularly to details, the outer links 3 of the lazy-tong structures are pivoted at their centers as at 4 to the inner links 5, said inner links 5 being connected by upper and lower rods 6 and 7, the 45 upper rods 6 being braced as at 8 to the links 5. The upper and lower ends of the links 3 project into sockets 9 and 10 in upper and lower brackets 11 and 12. These brackets 11 and 12 are provided on their inner 50 sides with spaced lugs 13 between which and said inner sides of the brackets 11 and 12, project the upper and lower ends of the inner links 5. Pivot bolts 14 are then passed through the socketed ends of the 55 brackets 11 and 12, through the upper and

lower terminals of the bars 3 and 5 through the lugs 13 and receive nuts 13'.

Revolutely mounted between depending ears 15 carried by the lower brackets 12, are a plurality of rollers 16, while the upper 60 brackets 11 carry knobs or buttons 17 by means of which the spring 2 is attached.

The upper portions of the end bars 3, at one extremity of the members 1, and the end bars 5 at the opposite extremity thereof are 65 provided with connecting boards 18 and 19 rigidly secured at their opposite ends to the above mentioned members. Connected to the inner corners of the boards 18 and 19 by hinges 21 and 22 respectively are head and 70 foot boards 23 and 24 which are adapted to be swung inwardly and rest upon the knobs 17 of the castings 11 and form a table top when the side members 1 are in folded position. 75

By this construction, it will be seen that I have produced a very simple, strong, and efficient folding bed with comparatively few moving parts, and which may be folded into a very small compass when not in use. 80

Although I have described my invention with considerable minuteness, I do not wish to be unduly limited to details, other than those set forth in the appended claim.

Having thus described my invention, what 85 I claim is:—

In a device of the character described, the combination with an inner and an outer series of parallel oppositely inclined bars, pivoted at their centers, of upper spring 90 securing and lower supporting brackets, said upper and lower brackets having sockets in their inner ends for receiving the terminals of the outer series of bars, and spaced integral lugs on their inner sides, between which 95 and said socketed ends, the terminals of the inner series of bars are adapted to lie and a bolt passing through said socketed ends, the two series of bars and the spaced lugs, whereby the terminals of the inner bars are 100 pivoted to said brackets and said brackets are rigidly secured on said outer bars.

In testimony whereof I have hereunto set my hand in presence of two subscribing witnesses.

ANDREW KALLIO.
